US00D910113S

(12) **United States Design Patent** (10) Patent No.: **US D910,113 S**
 Staudinger et al. (45) Date of Patent: ** Feb. 9, 2021

(54) **COMBINATION WRISTBAND AND LABEL FORM**(71) Applicant: **WARD KRAFT, INC.**, Fort Scott, KS (US)(72) Inventors: **Gina Staudinger**, Louisburg, KS (US); **Roger Davis**, Garland, KS (US); **Phil Quick**, Fort Scott, KS (US); **Roger Kraft**, Fort Scott, KS (US)(73) Assignee: **ward-kraft, inc.**, Fort Scott, KS (US)(**) Term: **15 Years**(21) Appl. No.: **29/668,923**(22) Filed: **Nov. 2, 2018**(51) LOC (13) Cl. **19-01**

(57) **CLAIM**

The ornamental design for a combination wristband and label form, as shown and described.

DESCRIPTION

FIG. 1 is a front view of the combination wristband and label form; and,

FIG. 2 is a back view of the combination wristband and label form of FIG. 1.

The dashed line in FIG. 1 illustrates printed indicia and forms a part of the claimed design. The broken lines in FIG. 2 illustrate environmental subject matter only and do not form a part of the claimed design.
